INVENTORS

BY Victor J. Evans

ATTORNEY

WITNESS: *John Donovan*

UNITED STATES PATENT OFFICE.

CHARLES A. TOZER AND PHIL HUNTER, OF MUSKOGEE, OKLAHOMA.

FUSE HOLDER.

Application filed August 24, 1925. Serial No. 52,038.

This invention relates to new and useful improvements in fuse cartridges and has for its primary object the provision of novel means for removably applying and clamping a fuse 5 within the cartridge without the use of tools.

A further object is the provision of novel means associated with the ends of the cartridge for protecting the insulator body of the cartridge as well as for effectively clamping 10 the fuse in the said ends of the body.

A further object is the provision of a device for this purpose characterized by simplicity in construction and reliability and efficiency in practical use.

To the attainment of the foregoing, the invention consists in the improvement as hereinafter described and definitely claimed.

In the drawings:—

Figure 1 is a side elevation of the improvement.

Figure 2 is a central longitudinal sectional view of the invention.

Figure 3 is an end view of the body of the improvement, the wedge carrying contact and 25 the cap being omitted.

Figure 4 is a view looking toward the inner end of the cap.

Figure 5 is a side elevation of the cap.

Referring now to the drawings in detail, 30 the numeral 1 designates the body of the improvement. The body is in the nature of a tube of fibre or other insulating material. Fixed, by means 2, in the ends of the body there are metal blocks 3 which are round in cross section and which are provided with longitudinal ports 4 which admit air into the body 1. The outer portion of each block 3 is threaded, as at 5, and each block is provided with a wedge-shaped opening, the lower 40 wall of which being flat, as at 6, and the upper wall arched and flared inwardly, as at 7. The ends of the fuse 8 rests on the shoulders provided by the walls 6 of the wedge-shaped openings in the blocks 3.

45 Designed to be screwed on the metal blocks 3 there are cap members 9. Revolubly arranged in each of the cap members there is a disc head 10 carrying on its inner face a wedge 11 complementary in shape to the walls 6 and 7 50 provided by the wedge openings in the blocks 3. The head 10 is held on the outer flange of the cap nut 9 by a ring 12, removable means 13 holding the ring positioned. This prevents the independent longitudinal move-

ment of the head and cap nut but permits of 55 the free turning of the cap nut on the head. Each of the metal heads 10 has on its outer face a knife blade contact 14, and each of the heads 10 is provided with spaced openings 15 that admit air into the cap nuts and through 60 the ports 4 to the interior of the fibre or insulator casing 1.

With our improvement it will be noted that the ends of the tubular insulator 1 are effectively protected by the metal blocks 3 and that 65 the metal wedge members 11 are influenced by the screwing of the cap nuts 9 to wedge engagement with the fuse blade 8. The construction is simple and is practically indestructible and the advantages thereof will, it 70 is believed, be perfectly apparent to those skilled in the art to which such devices relate, when the foregoing description is read in connection with the accompanying drawings.

Having described the invention, we 75 claim:—

A fuse holder, comprising a fibre tube, cross sectionally rounded metal members let in, secured to the ends of said tube and projecting beyond said ends, each of said members having an opening therethrough whose inner wall is flat and whose opposite wall is round and flared from the outer to the inner end of the said member, the flat walls of the said openings designed to provide a rest for 85 the ends of a fuse, metal disc heads having lugs complementary to the shape of the openings in the said members and designed to be received therein and to have their flat surfaces rest on the fuse, flanged screw caps arranged around the discs and threadedly engaging with the projecting ends of the metal members, and designed, when screwed on said members to force the lugs into frictional engagement with the walls provided by the 95 openings in said members and with the ends of the fuse ring members in the caps holding the disc heads against the flanges of said caps for preventing the independent longitudinal movement of the caps and disc heads 100 and permitting the turning of the caps on the disk heads, and said metal members and said disk heads having ports for admitting atmospheric air into the tube.

In testimony whereof we affix our signatures.

CHARLES A. TOZER.
PHIL HUNTER.
